TOILET DEVICE

George Wise, Washington, D. C.

Application August 19, 1941, Serial No. 407,509

4 Claims. (Cl. 132—79)

This invention relates to toilet devices, and its general object is to provide a device that includes a carrying case for toilet articles, particularly of the shaving type, and also means for supporting the case in open position with respect to a wash basin or the like, for the articles to be in convenient reach of the user, the case acting in the capacity of a shelf when in open position, and the supporting means being in the form of a clamp fixed to the case and designed to set up a clamping engagement with a faucet for detachable association therewith, therefore it will be seen that my device is extremely useful while travelling, in that the articles can be conveniently carried in the case and when it is desired to use the same, the clamp is attached to the faucet and the case is disposed to open position.

A further object is to provide a toilet device that includes a clamp for fastening and supporting the case with respect to and elevated above a faucet, and the clamp is foldable in compact form relative to the case, so that the device in its entirety will take up minimum space when not in use.

Another object is to provide a device that can be applied and removed with respect to a faucet in an easy and expeditious manner but casual removal or displacement is practically impossible.

A further object is to provide a device of the character set forth, that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a side view of my device attached to a faucet and with the case in open position.

Figure 2 is a front view of the device.

Figure 3 is a fragmentary bottom plan view, with the clamp in folded position.

Figure 4 is an enlarged fragmentary sectional view, with the clamp in folded position.

Referring to the drawing in detail, it will be noted that I have illustrated my device as being applied to the outlet spout of a double or mixing faucet, but it will be obvious that the device can be applied to any type of faucet or fixture, appropriate for receiving the jaws of the clamp for

the latter to support the case with respect to a wash basin or the like.

The case in the form shown is of the foldable book type generally used for a shaving or toilet kit, and includes a substantially rigid main wall creased or constructed in any manner to provide foldable sections 1 and 2, that are movable toward and away from each other for disposal of the case to open or closed position. Formed on or otherwise secured to each of the sections adjacent to and about the edges thereof is a flexible wall 3, and the walls 3 have the companion elements 4 of a slide fastener secured thereto about their edges, for securing the case in closed position. However, the case may be of any suitable construction and any type of fastening means may be provided for securing the same in closed position.

The clamp includes an elongated attaching plate 5 of sheet metal or the like, and it is of a length substantially coextensive with that of the main wall, to terminate short of opposed edges thereof, as the clamp is riveted or otherwise fixed to and along the center of the main wall to allow free folding of the case, as will be apparent.

Struck transversely of and from the plate 5 adjacent to and upon the opposite sides of the transverse center thereof are two pairs of ears 6 that are curved outwardly from the plate, but are directed toward each other, as best shown in Figure 4. Each pair of ears provide bearings for the bight portion 7 of an elongated substantially U-shaped member formed from heavy wire or the like, the bight portions bridging and pivotally mounted in companion ears for free swinging movement of the members toward and away from each other.

The limbs 8 of the members are crimped as at 9 from substantially midway their ends toward their outer ends, for a portion of their length, and the undulations formed by the crimped portions provide seats 10 for a purpose which will be later apparent. The limbs 8 are curved at their outer ends and those portions of the limbs between the outermost seats 10 and the curved outer ends provide companion clamping jaws 11 which cooperate with each other to engage the outer side faces of the spout A to set up a clamping engagement therewith, as best shown in Figure 2. That clamping engagement is brought about by a substantially square band 12 of wire or the like, which surrounds the limbs and is slidably mounted thereon for drawing the same together. The band 12 is receivable in any of the aligned seats 10 when the clamp is in use, as shown, to prevent any possibility of casual

removal or displacement of the jaws from the spout.

By that construction, it will be seen that the U-shaped members coact with each other to support the case in an elevated open position above the handles of the faucet, for the case to act in the capacity of a shelf, and so that the contents of the case will be in convenient reach of the user, the contents shown being shaving articles, that is a razor and a tube of shaving cream, but any type of articles can be placed and carried in the case, as will be apparent.

In order to urge and hold the U-shaped or supporting and clamping members in folded position against and in parallelism with the attaching plate, as shown in Figure 3, so that the device in its entirety will take up minimum space when not in use, such for example when placed in a travelling bag or medicine cabinet, I provide a spring for each U-shaped member and each spring is formed from a single strand of resilient wire, the strand being looped midway its ends to provide a free portion 13 engaged with the plate 5 between the pairs of ears. From the free portion 13 the strand is coiled about the bight portion of its member, between the ears 6, as at 14, and thence extends from the coiled portions into diverging portions 15 that terminate in hooks 16 engaged with the limbs 8. It will be noted as best shown in Figure 4 that the limbs 8 are curved adjacent their juncture with the bight portion thereof to provide seats 17 for the band 12, to allow the limbs to lie flat against the attaching plate 5, as will be apparent upon inspection of Figure 4.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A toilet device comprising a carrying case for toilet articles, a pair of elongated members pivotally connected at one of their ends to said case, clamping jaws formed on said members, means slidably mounted on said members for disposing the jaws in clamping engagement with a faucet for said members to support the case in open position above said faucet, and said

members being foldable in parallelism with said case when not in use.

2. A toilet device comprising a carrying case for toilet articles, a pair of elongated substantially U-shaped members having their bight portions pivotally connected to said case, clamping jaws formed on the outer end portions of the limbs of said members, a band slidably mounted on said limbs for disposing the jaws in clamping engagement with a faucet for said members to support the case in open position above said faucet, and springs bearing against said limbs for urging and holding the same in parallelism with said case when not in use.

3. A toilet device comprising a foldable case for toilet articles, a slide fastener for securing the case in closed position, a plate fixed to said case, ears struck from said plate and providing bearings, a pair of elongated U-shaped members having their bight portions mounted in the bearings for movement of the limbs of said members toward and away from each other, said limbs being crimped along portions of the length thereof to provide seats, clamping jaws formed on the outer end portions of said limbs, a band surrounding and slidably mounted on said limbs for disposing the jaws in clamping engagement with a faucet for said members to support the case in an open position above said faucet, said band being receivable in any of the seats to prevent removal of the jaws from their clamped position, springs mounted on the bight portions and bearing against the limbs for urging and holding said members in folded position with said limbs in parallelism with said plate, and said limbs being curved at their juncture with the bight portions to provide seats receiving the band therein when said members are in folded position to allow the limbs to bear against said plate.

4. A device comprising a carrying case, a pair of elongated members pivotally connected at one of their ends to said case, clamping jaws formed on said members, means mounted on said members for disposing the jaws in clamping engagement with suitable supporting means for said members to support the case in open position above said supporting means for the open portion of the case to form a shelf, and said members being foldable in parallelism with said case when not in use.

GEORGE WISE.
